SAFETY MATCH PACK

Herman F. Wachholz, Milwaukee, Wis.

Application July 23, 1936, Serial No. 92,057

3 Claims. (Cl. 206—29)

My invention relates to improvements in safety match packs.

The object of my invention is to provide a safety match pack provided with a sheath 5 wherein the matches, and a match striking surface, are receivable and reciprocable with provision for limiting the reciprocation so that a match may be removed from the pack, but the remaining matches must be completely housed 10 and protected by the sheath before a match striking operation upon the match striking surface can be accomplished. I thus provide a safety pack, in the use of which it is impossible for the user to accidentally ignite the entire pack 15 of matches by means of improper handling of the match while the striking operation is accomplished.

In the drawing:

Figure 1 is a plan view of my entire match pack 20 with the match comb slidably moved to an extreme position for a match removing operation.

Figure 2 is a view similar to Fig. 1, but with the match comb slidably moved to a match striking position.

Figure 3 is a perspective of my match comb removed from its protective sheath.

Figure 4 is a section on line 4—4 of Fig. 1.

Like parts are designated by the same reference characters throughout the several views.

I am aware that attempts have heretofore been made to protect matches in a match comb during a match striking operation, examples of such attempts being shown in the United States patents to Lindmark Number 1,863,724 and to 35 Willis Number 1,639,476. However, in the previous attempts to solve this problem it has always been possible to manipulate a match pack in such a way as to simultaneously expose the highly inflammable match heads and at least a usable portion of the match striking surface or abrasive. As a result, it is common knowledge that all the match heads of an entire match pack have been ignited in the hands of users with disastrous results upon numerous occasions.

In my construction I provide a match comb unit 10 including individual matches 11 with their heads 12. The base portion 13 of the match comb is preferably of extra length so that the abrasive surface 14 comprising the match striking surface upon which the match heads 12 may be frictionally engaged to ignite the heads, is spaced from the butts 15 of the matches.

As an extension of the comb I provide a portion 16 slotted at 17, thus providing the comb

10 and the extension 16 with the abrasive surface 14 as a unitary element.

I provide for this unitary element a sheath 18 preferably of simple and cheap construction as for instance a sheath of paper or light cardboard formed as an envelope comprising virtually a flattened tube having open ends at 20 and 21. One of the features of my invention is the formation of this envelope out of a single piece of paper-like material, folded to provide an underlying flap 22 through which a rivet may be extended as hereinafter described to make a complete assembly.

The comb unit is reciprocable in the sheath 18 as shown clearly in Figs. 1 and 2 from a "closed" position in which the only portion of the comb which is exposed is the abrasive coated portion 14 to an extreme point of reciprocation in the "open" position in which the matches are exposed so that individual matches may be torn from the comb.

A rivet 19 or other element such as a clip or any device to engage the comb and envelope to limit the extent of reciprocation of the comb in the sheath completes the structural elements 25 of my invention. The rivet or clip 19 may extend completely through the envelope or sheath 18 as shown clearly in Fig. 4 or it may comprise any mechanical device for inter-engagement of the sheath and comb to limit the extent of reciprocation as aforesaid.

From the above description it will be seen that no match striking operation upon the abrasive surface 14 can be accomplished by the user unless the match heads 12 are within the sheath 30 and protected from flying sparks.

I claim:

1. In a match pack, a sheath comprising a sheet of material folded upon itself and provided with a flap, a slotted match comb unit in the folded sheet material and a clip extending through the flap and the folds of sheet material and extending through the slot in the comb unit whereby to form an assembly in which the sheet material comprises an envelope for the unit and the unit is restrictedly reciprocable therein.

2. In a match pack, a sheath comprising a sheet of material folded upon itself to provide an envelope, a slotted match comb unit in the envelope and a clip extending through the envelope and through the slot in the comb whereby to assemble and bind the envelope and comb in a unitary assembly wherein the comb is restrictedly reciprocable.

3. In a match pack, a sheath comprising a

sheet of material folded upon itself to provide an envelope, a match comb provided with matches arranged with their heads at one end of the comb and an abrasive match lighting material 5 at the other end thereof, said comb having a slot parallel with the matches and having a lineal extent less than the distance between the match

heads and said abrasive material, and a clip through said envelope and through the slot in the comb whereby to bind the comb in unitary assembly wherein the comb is restrictedly reciprocable.
